Rubin Krivsky, 4 Sherman Drive, Spring Valley, N.Y.
Filed Aug. 4, 1964, Ser. No. 387,376
5 3 Claims. (Cl. 312—341)

Our invention relates to drawer slides generally and specifically to a universal drawer slide mountable in the three planes of space.

A wide variety of well known drawer slides comprise generally a rail slidably engaged to a channeled track. Usually the channeled track is secured to a cabinet frame into which the drawer seats; the channeled track lying parallel to the direction of movement of the drawer. The rail is mounted to the track on the drawer and is generally parallel thereto.

Known drawer slides must frequently be fabricated specifically for either the right or the left side of the drawer. Obviously, this increases costs of manufacturing. In addition, it is becoming more desirable to position the drawer slide on the underside of a structural member such as a countertop, vanity top and the like, rather than fasten the track to the cabinet frame along the side of the drawer.

It is also becoming more desirable to mount such a cooperative channeled track and rail beneath the drawer itself, securing the channeled track to a member of the cabinet frame extending either parallel to the direction of movement of the drawer or to a member extending perpendicular thereto.

Today, known channeled tracks are mounted to members of the cabinet frame lying in a plane parallel to the plane of the side of the drawer by passing screws through holes in the back of the track. However, such fastening means cannot be employed when the back of the track does not lie against the cabinet member. Moreover, in many situations the cabinet frame member lying parallel to the back of the channeled back is inaccessible and, therefore, it is more desirable to approach the frame member from a direction facing the end of a track or the top and bottom thereof. No known channeled tracks can be mounted in all three planes of space as aforesaid. Rather, each must be particularly fabricated for its particular fashion of mounting.

Therefore, it is among the objects and advantages of our invention to provide a universal drawer slide which may be mounted to cabinet frame members lying in a plane parallel to the back thereof as well as in a plane lying perpendicular to the back thereof either above or beneath the track or lying in a plane parallel to the end of the track.

Another object of our invention is to provide a universal drawer slide which may be mounted to cabinet frame members extending in all three planes of space, the track being secured to either one or two of such planes simultaneously.

A further object of our invention is to provide a universal drawer slide mountable beneath a cabinet frame member parallel to the plane of the drawer and perpendicular to the plane of the back of the slide, the slide being positioned on both sides of the drawer parallel to its direction of movement.

Still another object of our invention is to provide a universal drawer slide having an angular mounting member pivotally mounted on the back of the channeled track, the mounting member being rotatable about 360° parallel to the said back.

These objects and advantages as well as other objects and advantages may be achieved by our invention an embodiment of which is illustrated in the drawings in which:

2

FIGURE 1 is a side elevational view of a typical channeled track having our angular mounting members pivotally engaged thereto; the dotted portions of the drawing illustrating the mounting members in different positions;

FIGURE 2 is a top plan view of the channeled track illustrated in FIGURE 1;

FIGURE 3 is an end elevational view of a channeled track having our angular mounting member pivotally mounted thereto showing a complementary rail engaged thereto;

10 FIGURE 4 is a view in perspective of our channeled track mounted beneath a countertop suspending a drawer thereunder;

15 FIGURE 5 is a view in perspective showing our channeled track mounted to a cabinet frame member positioned beneath but generally parallel to the plane of the back of the track;

20 FIGURE 6 is a view in perspective of our channeled track mounted to a cabinet frame member positioned above and generally parallel to the plane of the back of the track;

25 FIGURE 7 is a view in perspective of our channeled track mounted to a cabinet frame member extending perpendicular to the longitudinal axis of our channeled track.

Referring now to the drawings in detail, our invention comprises a channeled track 11 having a generally conventional form. The channeled track comprises a generally elongated rectangular, flat back 12 having a pair of 30 90° offset members 13 and 14 on the top and bottom thereof respectively. Formed integral with the top member 13 on the side opposite the back 12 is an externally convex rib 15. Similarly formed on the bottom member 14 opposite the back 12 is an opposed externally convex rib 16.

35 A rail 17 is slideably engaged to the channeled track 11 as is illustrated in FIGURE 3. The rail 17 comprises a generally rectangular, flat back 18 having formed on the top and bottom thereof a pair of externally concave arcuate ribs 19 and 20. A ball bearing carrier (not illustrated) is seated within the channeled track 11 supporting ball bearings 21, 21 between the respective arcuate ribs 15, 19, 20 and 16.

The channeled track and rail as aforesaid is of a conventional design and is not critical to our invention.

40 A pair of mounting members are pivotally mounted to the back 12 of the channeled track 11. The pivotal mounting member 22 is generally L-shaped having a back member 23 and a flange 24. The back member 23 is pivotally engaged to the back 12 of the channeled track 11 by a rivet 25 extending therethrough. The flange 24 of the mounting member 22 is provided with two circular openings 26, 26 and an elongated slot 27 located therebetween.

45 FIGURE 1 illustrates in broken lines two additional positions that the mounting members 22 may assume. On the left, the mounting member has been rotated 180° so that the flange 24 is positioned above the track 11 whereas on the right hand side on that figure, the flange 24 is perpendicular to the longitudinal axis of the track 11. It should be noted that the flange 24 when parallel to the longitudinal axis of the track 11 lies beneath the lowermost extension of the arcuate rib 16 or above the uppermost extension of the arcuate rib 15.

50 In FIGURE 4, a typical mounting for a vanity drawer is illustrated. The respective mounts are pivoted until the flange 24 lies parallel to the longitudinal axis of the track 11 extending above the top rib 15. The flange 24 is then secured to the bottom of the vanity cabinet 28 by means of screws or the like. The drawer 29 is thus mounted beneath the vanity top 28. Of course, as is illustrated, 55 two opposed tracks are employed and the rails 17 are mounted to the sides 30, 30 of the drawer 29.

FIGURE 7 illustrates still another mounting technique wherein the mounting member 22 is oriented at 90° to the longitudinal axis of the channeled track 11 being secured to a cabinet frame member 33 which extends perpendicular to the longitudinal axis of the track 11. Of course, the entire view in FIGURE 7 could be rotated 90° in order to illustrate a bottom channeled track support for a drawer.

What is claimed:

1. A universal drawer slide comprising:

- (a) a channeled track and complementary rail, the track having a pair of longitudinal edges,
- (b) at least one mounting member engaged to the track,
- (c) a back member on the mounting member pivotally engaged to the track,
- (d) a flange on the back member, and
- (e) the plane of the flange extending above one of the edges of the channelled track when the said plane of the flange is parallel to the longitudinal axis of the track.

2. A universal drawer slide comprising:

- (a) a channeled track and complementary rail, the track having a pair of longitudinal edges,
- (b) at least one mounting member engaged to the track,
- (c) a back member on the mounting member pivotally engaged to the track and rotatable about 360 degrees,
- (d) a flange on the mounting member extending away from the track, and

(e) the plane of the flange extending above one of the edges of the channelled track when the said plane of the flange is parallel to the longitudinal axis of the track.

3. A universal drawer slide comprising:

- (a) a channeled track and complementary rail, the track having a generally flat back joining a pair of longitudinal edges,
- (b) at least one mounting member engaged to the track,
- (c) a back member on the mounting member pivotally engaged to the track and rotatable about 360 degrees,
- (d) a flange on the mounting member generally perpendicular to the back of the track extending in a direction away therefrom, and
- (e) the plane of the flange extending above one of the edges of the channelled track when the said plane of the flange is parallel to the longitudinal axis of the track.
